G. W. WACKER.

PORTABLE ELECTRIC LIGHT.

APPLICATION FILED APR. 22, 1916.

1,238,850.

Patented Sept. 4, 1917.

UNITED STATES PATENT OFFICE.

GEORGE W. WACKER, OF RUTHERFORD, NEW JERSEY, ASSIGNOR TO NATIONAL CARBON COMPANY, OF NEW YORK, N. Y., A CORPORATION OF NEW JERSEY.

PORTABLE ELECTRIC LIGHT.

1,238,850.

Specification of Letters Patent.

Patented Sept. 4, 1917.

Application filed April 22, 1916. Serial No. 92,847.

To all whom it may concern:

Be it known that I, GEORGE W. WACKER, a citizen of the United States, residing at Rutherford, in the county of Bergen and 5 State of New Jersey, have invented certain new and useful Improvements in Portable Electric Lights, of which the following is a specification, reference being had therein to the accompanying drawings, forming part 10 thereof.

My invention relates to portable electric lights or flashlights and relates more particularly to tubular flashlights in which a metal lamp socket is insulated from a lamp- 15 supporting metal reflector. Tubular flashlights of this kind having an electrically conductive lamp socket insulated from the exposed metal fittings or casing parts are disclosed in the patent to Conrad Hubert 20 No. 1,157,395 of October 19, 1915, for a portable electric light, and also in the patent to Conrad Hubert No. 1,220,634, of March 27, 1917, for a portable electric light.

An important object of my present invention is to produce a construction which is simpler, stronger, more reliable and less expensive to manufacture than constructions heretofore employed. Another important object of my invention is to provide, in a construction having an insulated lamp socket, for the employment or embodiment therein of the improved lamp socket which forms the subject of my application for patent filed on even date herewith as 30 Serial No. 92,846. Other objects and advantages of my invention will hereinafter appear.

My invention includes an annulus of insulating material upon one edge of which 40 an edge of the metal reflector is turned over in gripping relation and upon the other edge of which a contact-making or circuit-completing flange extending from the electrically conductive lamp socket is turned 45 over in gripping relation, whereby the electrically conductive lamp socket is supported upon and insulated from the reflector by the intermediary insulating annulus. My invention more particularly includes an annular insulating disk to the inner edge of 50 which the inner edge of the reflector is secured and to the outer edge of which the contact plate which carries the lamp socket is secured, the lamp socket projecting, in 55 spaced relation to the reflector, into a cen-

tral socket-receiving opening which the reflector provides. My invention also includes other features of construction and combinations of parts as will appear from the following description.

I shall now describe the tubular portable electric light illustrated in the accompanying drawings embodying my invention and shall thereafter point out my invention in claims.

Figure 1 is a central longitudinal section of a portable electric light in which my invention is embodied, with the circuit in the closed condition.

Fig. 2 is an elevation, partly in section 70 and with parts omitted, as seen from above in Fig. 1 and with the circuit in the open condition.

Fig. 3 is a transverse section on a plane indicated by the lines 3—3 of Fig. 1 as 75 viewed from the right.

Fig. 4 is an enlarged partial transverse section on a plane indicated by the lines 4—4 of Fig. 1 as viewed from the left, the lamp and the outer casing being omitted. 80

Fig. 5 is a similar section on a plane indicated by the lines 5—5 of Fig. 1 as viewed from the right.

Fig. 6 is an enlarged longitudinal section in the plane of Fig. 1 of the lamp socket 85 and its insulating and supporting means, including the reflector, and showing the lamp in elevation.

The particular tubular portable electric light or flashlight illustrated in the accompanying drawings as embodying my invention has a battery-containing casing which includes a main cylindrical or tubular part 1 of metal. A usual metallic end cap 2 is screw-threaded over the rear end of the 95 tube 1 and is provided at the inside with a usual battery-supporting electrically conductive spiral thrust spring 3.

The casing contains a battery shown as comprising two cells having a zinc cup 4 forming one terminal of the cell and having a carbon central end terminal 5, these battery cells being contained in a usual paper insulating tube 6. The zinc cup 4 of the cell at the rear end of the casing, forming 100 the zinc terminal of the battery, is in contact with the conductive thrust spring 3, and the carbon terminal 5 of the cell at the front end of the casing, forming the other terminal 105 of the battery, is in contact with the central 110

terminal 7 of an ordinary miniature incandescent lamp having a bulb 8 and a usual annular screw-threaded base 9 which forms the other terminal of the lamp.

5 A usual flanged metal ring 10 is screw-threaded over the forward end of the metal casing tube 1 and holds in place a usual lens 11 and a lamp-supporting metallic reflector 12 which is shown as held at its out-turned outer or peripheral edge between the lens 11 and an inturned flange shown as provided upon the outer screw-threaded end of the tubular casing part 1. It is to be noted that the metallic reflector 12 is in electrically conductive relation with the metal casing tube 1 and the metal end ring 10, and is therefore electrically connected to the zinc terminal of the battery through the casing tube 1, the metal end cap 2 and the thrust spring 3.

10 Means involving my invention and now to be described are provided for supporting the lamp from the reflector 12 in insulated relation thereto, so that the lamp circuit may be completed through its terminal 9, which forms also a supporting base for the lamp.

15

20

25

25 The metallic reflector 12 is provided with a central tubular extension which provides a central socket-receiving opening, this tubular extension being shown as comprising 30 a larger forward part 13 and a reduced rear part 14 between which is formed an inwardly directed outer shoulder 15, as clearly appears in the drawings, particularly in Fig. 6. An annular insulating disk 16 of suitable insulating material such as vulcanized fiber, for 35 example, fits snugly over the neck 14 and abuts against the shoulder 15 and is firmly gripped and securely held in place by means of a flange 17 turned over outwardly from 40 the inner edge of the neck 14 of the tubular extension from the reflector 12, the inner edge of the annular insulating disk 16 being thus gripped and held by the inner edge of the reflector 12 so that the insulating disk 45 16 is securely supported upon the reflector 12.

50 A metallic lamp socket 18 projects outwardly into the metal socket-receiving opening provided by the reflector 12 in spaced relation to the reflector at its neck or reduced part 14. The tubular lamp socket 18 is supported by a circuit-completing plate or contact plate 19, shown as formed in one piece with or from the same piece of metal as the 55 lamp socket 18 and shown as forming a flange at the inner end of the tubular lamp socket 18. The contact plate 19 is spaced backwardly away from the turned-over flange 17 of the reflector by means of an annular off-set or short cylindrical portion 20 which forms outwardly therefrom a flat annular seat or shoulder 21 having an outer 60 peripheral rim 22 forming with the shoulder 21 a cup or receptacle into which the 65 outer edge or peripheral portion of the an-

nular insulating disk 16 snugly fits, and the free outer edge of the short cylindrical cup part 22 is turned over inwardly upon the outer edge of the insulating disk 16 to form an inturned gripping flange 23 which firmly 70 clamps the outer edge of the insulating disk 16 against the shoulder 21, whereby the contact plate 19 and the lamp socket 18 are supported by the intermediate annular insulating disk 16 upon the metallic reflector 12 75 and are electrically insulated therefrom, so that the lamp circuit is interrupted at this point. The terminal of the lamp formed by its screw-threaded base 9 is in electrically conductive relation with the tubular socket part 18 but is insulated from the reflector 12 80 and the outer metal casing parts by the annular insulating disk 16 by which the lamp socket 18 and lamp are supported.

Any suitable circuit-controlling means 85 may be provided for electrically connecting the contact plate 19 with some metallic part of the casing which is in electrical connection with the zinc terminal of the battery through the thrust spring 3. In the construction illustrated in the drawings, a longitudinally movable contact strip 24 is turned inward at its forward free end for circuit-closing engagement with the contact plate 19, as shown in Fig. 1, and may at 90 95 will be moved forward into its circuit-closing position or retracted backwardly therefrom, as shown in Fig. 2, by means of a manually actuated slide 25 at the outside of the tubular casing part 1 and connected to 100 the contact strip 24 by tubular rivets 26 which pass through a slot 27 in the tubular casing part 1 and connect the slide 25 to the movable contact strip 24. The circuit will be maintained in the open or in the closed 105 condition by friction of the movable circuit-controlling parts, this friction being increased by means of a strip 28 of suitable material, such as fiber, interposed between the slide 25 and the outer surface of the 110 metal casing tube 1, this fiber strip 28 also preventing the scratching of the polished outer surface of the casing tube 1, the fiber strip 28 being held in place by the tubular rivets 26, as appears in Fig. 1. 115

The lamp socket or tubular socket member 18 illustrated in the drawings is of the construction which forms the subject of my hereinbefore mentioned application for patent for lamp socket. This socket member 18 is a smooth cylindrical tube which freely receives the screw-threaded lamp base 9 of the lamp and at one of its sides is provided with a transversely slotted opening 29 which is slightly inclined to correspond with the screw-thread of the lamp base 9. The lamp base 9 is held in good conductive relation with the socket member 18 and is gripped and held against unscrewing by means of a split ring 30 of spring wire which engages 120 125 130

and grips the outside of the tubular socket member 18 and which has at one end a straight portion, as appears in the drawings, which enters or passes transversely through 5 and beyond the slot 29 in the tubular socket member 18 and engages and presses upon the lamp base 9 in the groove formed by its screw-thread, it being noted that the resilient lamp-holding split ring 30 does not come 10 in contact with the adjacent neck 14 of the reflector 12, from which the lamp socket 18, split ring 30 and lamp base 9 are insulated by the means hereinbefore described involving my present invention. The construction 15 provided by my present invention is particularly adapted for supporting the lamp socket of my invention with which it is shown as embodied in a single construction. However, in carrying out my present in- 20 vention a different form of lamp socket could be employed, for example, the usual screw-threaded form of lamp socket.

It is obvious that various modifications may be made in the construction shown in 25 the drawings and above particularly described within the principle and scope of my invention.

I claim:

1. A portable electric light having, in 30 combination, a conductive reflector provided with a socket-receiving opening, a conductive lamp socket in the opening and spaced out of contact with the reflector, and an annular insulating disk supporting the lamp 35 socket on the reflector in insulated relation therewith and to the inner edge of which the reflector is secured and to the outer edge of which the lamp socket is secured.

2. A portable electric light having, in 40 combination, a conductive reflector, an annular insulating disk engaged at its inner edge by and supported upon the reflector, a conductive contact plate engaging the outer edge of the insulating disk and supported 45 thereon, and a conductive lamp socket carried by the contact plate in spaced relation to the reflector.

3. A portable electric light having, in

combination, a conductive reflector provided with a socket-receiving opening, an annular insulating disk upon the inner edge of which the inner edge of the reflector is turned over to grip the insulating disk, a conductive contact plate turned over upon and gripping the outer edge of the insulating disk, and a conductive lamp socket carried by the contact plate and projecting into the socket-receiving opening of the reflector in spaced relation to the reflector.

4. A portable electric light having, in 60 combination, a conductive reflector, an annulus of insulating material having opposite edges upon one of which the reflector is turned over and grips, and a conductive lamp socket having a contact flange turned 65 over upon and gripping the other edge of the insulating annulus.

5. A portable electric light having, in combination, a conductive reflector provided with a socket-receiving opening, an annulus 70 of insulating material having opposite edges upon one of which the inner edge of the reflector is turned over and grips, a conductive contact plate turned over upon and gripping the other edge of the insulating 75 annulus, and a conductive lamp socket carried by the contact plate and projecting into the socket-receiving opening of the reflector in spaced relation to the reflector.

6. A portable electric light having in com- 80 bination, a conductive reflector provided with an opening, an annular insulating disk upon the inner edge of which the inner edge of the reflector is turned over to grip the insulating disk, a conductive contact plate the 85 outer edge of which is turned over upon and grips the outer edge of the insulating disk and which inwardly from its outer turned-over edge is provided with an annular offset which spaces the contact disk from the 90 turned-over inner edge of the reflector, and a conductive lamp socket carried by the contact plate in spaced relation to the reflector.

In testimony whereof I have affixed my signature.

GEORGE W. WACKER.
